United States Patent Office.

JOSEPH R. SMITH, OF CHICAGO, ILLINOIS, ASSIGNOR TO CORNELIUS WALSH, OF NEWARK, NEW JERSEY.

Letters Patent No. 95,944, dated October 19, 1869.

IMPROVEMENT IN TRAVELLING-BAGS.

The Schedule referred to in these Letters Patent and making part of the same.

To all whom it may concern:

Be it known that I, JOSEPH R. SMITH, of Chicago, in the county of Cook, and State of Illinois, have invented a new and useful Improvement in Travelling-Bags, and that the following is a sufficiently full, clear, and exact description to enable one skilled in the art to which my invention appertains to carry it into effect, reference being had to the accompanying drawings, which are made part of this specification.

The subject of my invention is a travelling-bag, having a frame of novel construction, and metallic protectors or shields to protect the leather or cloth at the corners of the frame.

Figure 1 of the drawing represents a perspective view of a travelling-bag, having my improvements applied, a portion of the cover being broken away to more fully explain its construction.

Figure 2 is a perspective view of the frame, detached and open.

Figure 3 is a sectional view of one corner of the bag.

The ends *a* of the band *A* of the frame are bent around the lower corners, so as to obviate the liability of the band to be knocked off at this place, and are connected by a strip of metal, *B*, which in the manufacture of the bag, passes inside the bottom, which is riveted thereto, being thereby adapted to be made in one piece, and the separate covering of its support obviated, and which is made of thicker metal than the body of the frame, as represented, so as to afford the necessary rigidity of support for the ends of the frame.

The ends *c* of the side or jaw *C* of the frame, to which the band is attached, are preferably bent at right angles, and extend across the band, where they have one side of the hinge formed in them by notching and bending, or in other suitable manner, the other half of the hinge being formed in the ends of the side *D*, which forms the other jaw of the frame, and the two parts united by the customary pintles *E*, which may be in the form of rivets, as shown.

The frame, constructed as above described, adapts corner-shields, or protectors *F*, to be readily applied. These are preferably made by casting, in the form shown, and are applied after the frame is covered, and riveted through the leather or cloth and the band at the bottom and ends, as shown in fig. 3.

Any suitable fastening, or fastenings *G H*, may be applied to the bag, in the usual or any suitable manner.

The several parts of the frame may be united by rivets, as shown, or otherwise, and be made of any suitable material.

By obviating the necessity of a seam in the bottom of the bag, and of the covering of the support of the bottom, as above explained, great saving in material and time, and consequently in the cost of the manufacture of the bag, is secured, while at the same time a much more neat, strong, and durable article is produced.

The frame, further, separately is adapted by my improvement to be much more expeditiously and cheaply manufactured, and is stronger, smoother, and lighter in proportion than the old form.

Having thus fully described my invention,

I claim as new therein, and desire to secure by Letters Patent—

1. The band *A*, having its ends *a a* bent around the hinge-corners of the frame, and connected by a separate strip or brace, *B*, of greater strength or stiffness, substantially as represented and described, for the purposes set forth.

2. The band *A*, having its ends *a a* bent around the hinge-corners of the frame, and united by a separate stiff strip or brace, *B*, in combination with the corner-shields or protectors *F*, applied externally of the cover, as represented and described, for the purpose set forth.

JOSEPH R. SMITH.
